UNITED STATES PATENT OFFICE.

HENRY A. LOGAN, OF CEDAR GROVE, LOUISIANA, ASSIGNOR OF ONE-FOURTH TO MACK D. LOGAN, OF SHREVEPORT, LOUISIANA.

MONKEY WRENCH.

Application filed May 28, 1925. Serial No. 33,524.

To all whom it may concern:

Be it known that I, HENRY A. LOGAN, a citizen of the United States, residing at Cedar Grove, in the parish of Caddo and State of Louisiana, have invented certain new and useful Improvements in Monkey Wrenches, of which the following is a specification, reference being had to the accompanying drawings.

10 This invention relates to wrenches, and particularly to monkey wrenches.

The general object of the invention is to provide a wrench of this character in which the jaws automatically close upon the nut or other work as the wrench is turned to turn the work, and in this connection to provide a wrench wherein one of the jaws is adjustable to adapt the wrench to different sizes of work.

20 A further object is to provide a construction of this character wherein the principle of the toggle is used for the purpose of causing the closing of the jaws, thus causing the jaws to close with great strength upon the work.

Other objects will appear in the course of the following description.

My invention is illustrated in the accompany drawing, wherein:

30 Figure 1 is a side elevation of a monkey wrench constructed in accordance with my invention showing the jaws open;

Fig. 2 is a like view to Fig. 1 but showing the jaws closed upon the work;

35 Fig. 3 is a front elevation of the construction shown in Fig. 1; and

Fig. 4 is a fragmentary rear elevation of the handle 10.

Referring to the drawing, 10 designates 40 the handle of the wrench which is formed with an offset 11 at its upper end. Above the offset 11 one side of the wrench is cut away, as at 12, to form a recess and the lower wall of this recess is vertically slotted, as at 13.

Pivoted within this recess is a toggle link 15 having a tongue 14 extending into the slot 13 and pivoted to the handle by means of the pivot 16. The offset portion 11 is formed with a transversely extending slot 17 and the handle upon its inside face is formed with a longitudinally extending recess 18 opening into this slot 17 and opening upon the face of

the handle. A bore 19 extends from the slot 17 longitudinally through the handle.

Operating within this bore is the screw-threaded rod 20 and a nut 21 is disposed within the slot 17 engaging this screw so that when the nut is turned the rod will be raised 60 or lowered. The upper end of the rod is formed with a bifurcated head 22, and pivotally connected at 22^a to this head is a shank 23 having a tongue extending into the bifurcation of the head. This shank 23 passes loosely through a sliding jaw 24 and carries at its upper end a jaw 25 confronting the jaw 24. The confronting faces of the jaws 24 and 25 are serrated, toothed or otherwise formed. One face of the sliding jaw 24 has a downwardly extending tongue 26 which engages in the bifurcated upper end of the link 15 and is pivoted thereto by a pivot pin 27.

In the operation of this device, the nut 75 21 is turned so as to shift the rod 20 longitudinally in one direction or the other. When the rod is shifted toward the jaw 24, the jaw 25 will be carried away from the jaw 24 so as to increase what may be termed the normal space between the jaws;

and a reverse movement of the nut will reverse the movement of the jaws and draw the upper jaw nearer to the jaw 24. When the jaws have been brought into approximate position to grasp a nut, the jaws are placed upon the nut or other work and the handle turned toward the left in Fig. 2.

This acts to swing the handle with reference to the link 15 and with reference to the shank 23, the shank 23 pivoting on the pivot pin 22^a. This acts to shorten the distance between the jaw 25 and the sliding jaw 24 and the turning of the handle causes it to have an angular relation to the link 15 85 and shank 23, as illustrated in Fig. 2. Thus the two jaws are caused to relatively move toward each other and jam upon the nut. A

reverse movement of the handle will act to open the jaws until the link 15 comes in 100 contact with the flat face 11^a of the recess within which the link is pivoted. This flat face then acts to stop the movement of the link toward the handle beyond a position where the link 15 is parallel to the longitudinal axis of the handle, as shown in Fig. 1.

While I have illustrated certain details

of construction and arrangement of parts which I believe to be particularly effective, I do not wish to be limited thereto, as it is obvious that many changes might be made in the smaller details without departing from the spirit of the invention. The wrench may be made of any suitable material, but preferably the handle will be faced with wood.

10 It will be understood that this wrench is designed to be used as a pipe wrench as well as a nut wrench or used for any purpose for which it is adapted. The particular advantage of the device resides in the simplicity of the wrench and the power with which the movable jaw is forced toward the fixed jaw by the toggle link when the wrench is put in operation.

I claim:—

20 1. A wrench of the character described comprising a handle, a screw-threaded rod having longitudinal movement within the handle, a nut engaging the rod and the handle whereby the rod may be shifted longitudinally relative to the handle, a jaw shank pivotally connected to the rod and carrying a jaw at its outer end, a sliding jaw mounted upon the shank and shiftable longitudinally thereon, a link pivotally connected to the handle and to the sliding jaw whereby when the jaws grasp an object and the handle is shifted in one direction the handle and jaw shank will take an angular relation and cause the jaws to move relatively toward each other and means for limiting the movement of the link toward

the handle and into parallel relation therewith.

2. A wrench of the character described comprising a handle having a longitudinally extending bore and a transverse slot, a screw-threaded rod mounted in the bore and longitudinally movable therein, a nut disposed in said slot and engaging the screw-threaded rod, a jaw shank pivotally connected to one extremity of the screw-threaded rod and having a jaw at its opposite end, a sliding jaw mounted upon the shank, and a link pivotally connected to the handle and normally extending parallel to the shank, the sliding jaw having a tongue pivotally connected to the link.

3. A wrench of the character described comprising a handle having a longitudinally extending bore and a transverse slot, a screw-threaded rod mounted in the bore and longitudinally movable therein, a nut disposed in said slot and engaging the screw-threaded rod, a jaw shank pivotally connected to one extremity of the screw-threaded rod and having a jaw at its opposite end, a sliding jaw mounted upon the shank, and a link pivotally connected to the handle and normally extending parallel to the shank, the sliding jaw having a tongue pivotally connected to the link, the handle at its end nearest the jaws being recessed to receive the adjacent end of the link.

In testimony whereof I hereunto affix my signature.

HENRY A. LOGAN.
